HONING ATTACHMENT FOR LATHES
 Richard G. Norris, P.O. Box 14, Cumberland, R.I. 02838
 Filed Aug. 5, 1964, Ser. No. 387,625
 3 Claims. (Cl. 51—259)

This invention relates to a honing attachment for a lathe or the like and has for its principal object the provision of an adjustable attachment which can be applied to lathes of varying sizes.

Another object of the invention is to provide a novel honing attachment for a lathe, which may be readily secured in a vertical relationship to the normal ways of a lathe.

A further object of the invention is the provision of a separate drive mechanism for the honing attachment of this invention, which drive means may be readily secured in a collet or other chuck of a lathe which drive attachment may be readily engaged with the honing attachment.

A still further object of the invention is the provision of a honing attachment for a lathe which may be readily secured to the ways of a lathe and may be adjusted in height relative thereto so as to be placed in proper operating position relative to the spindle of the lathe.

A still further object of the invention is to provide a novel honing attachment which is economically manufactured, easily used and maintained for the purposes intended.

With these and other objects in view, the invention consists of certain novel features of construction as will be more fully described and particularly pointed out in the appended claims.

In the drawings:

FIG. 1 is an elevational view partly in section showing my improved attachment as applied to a lathe; and

FIG. 2 is a view of reduced scale.

Referring now to the drawings, 10 generally designates a lathe bed, while 11 generally designates the head stock assembly which consists basically of a drive spindle 12 to which a number of attachments may be added. For example in the drawings, there is shown a key type chuck 13 of the usual form.

The honing attachment assembly includes a main support member generally indicated at 15 which includes a tubular member or post-like member 16 that rises vertically from a rectangular base member 17. Within the tubular support member 16, there is received a pair of spaced bearings 18 and 19 which have journaled therein a main shaft 20. On the upper end of the shaft 20, there is suitably secured a table 22 which may be fastened to the shaft by means of a socket-head screw such as 23. The table 22 has provided on the periphery thereof a lip 24 such that a recess is formed to receive an abrasive wheel 25. On the lower side of the table 22 a bevel gear 26 is fastened, which gear has a plurality of teeth 27 that are adapted to engage the drive pinion 28, the shaft 29 of which is received within the drill chuck 13. It will, of course, be appreciated that it is not necessary to utilize a drill chuck as other forms of drive means, for ex-

2

ample, three or four jawed chucks and collets are equally suitable.

Received on the shaft 20 are a pair of collars 30 and 31, the collar 30 bearing against a washer-like element 32 resting on the upper end of the tubular support member 16. The collar 30 is retained in position by a set screw 33, and serves to support the table and gear 26 in proper position for driving by pinion 28, while collar 31 limits upward movement and similarly has a retaining set screw 34. This particular arrangement permits the shaft 20 to be adjusted vertically with respect to the tubular support 16 to thereby meet the various requirements of lathe constructions and particularly spindle heights above the lathe bed.

In order to permit adjustment of the honing assembly transversely of the machine, the base 17 is provided with an adjustable clamp bar 40 with a bolt 41 passing up through the base and being held in position by a nut 42. Thus, the base 17 may be slid along the lathe ways into proper engaging position so that the bevel gear 26 will engage the drive pinion 28 and then secured in position by tightening the nut 42 after the bar member 40 has been swung transverse of the lathe bed so as to engage the underside thereof.

25 I claim:

1. A honing attachment for a machine tool having a generally horizontal bed and a horizontal rotating shaft, comprising a base to engage the machine tool bed, means to clamp the base to the bed, said base being provided with an upstanding tubular member, a vertical shaft journaled in said tubular member, a table secured to the upper end of said shaft, abrasive material carried by the upper side of said table, power engaging means secured to the under side of said table and engaged by a driving means adapted to be attached to said rotating shaft of the machine tool.

2. A honing attachment as in claim 1 wherein collars are secured to said vertical shaft above and below said tubular member to vertically adjustably locate said shaft in said member.

3. A honing attachment as in claim 1 wherein said power engaging means and driving means are bevel gears.
